COMBINED TOILET SEAT AND COVER
THEREFOR

Jon W. Hauser, Oak Park, Ill., assignor to Hawley
Products Company, St. Charles, Ill., a corporation of Delaware

Application November 1, 1952, Serial No. 22,099

Term of patent 14 years

(Cl. D4—5)

To all whom it may concern:

Be it known that I, Jon W. Hauser, a citizen of the United States, residing at Oak Park, in the county of Cook and State of Illinois, have invented a new, original, and ornamental Design for a Combined Toilet Seat and Cover Therefor, of which the following is a specification, reference being had to the accompanying drawing, forming part thereof in which:

Fig. 1 is a top plan view of the combined toilet seat and cover therefor showing my new design;

Fig. 2 is a side elevational view;

Fig. 3 is a front elevational view;

Fig. 4 is a rear elevational view; and

Fig. 5 is a bottom plan view thereof.

The broken line showing is for illustration purposes only.

I claim:

The ornamental design for a combined toilet seat and cover therefor, substantially as shown and described.

JON W. HAUSER.
